United States Patent Office.

SAUNDERS HUBBELL, JR., OF WEST SALEM, OHIO.

Letters Patent No. 79,981, dated July 14, 1868.

IMPROVEMENT IN CATCH FOR MONEY-DRAWERS.

The Schedule referred to in these Letters Patent and making part of the same.

TO ALL WHOM IT MAY CONCERN:

Be it known that I, SAUNDERS HUBBELL, Jr., of West Salem, in the county of Wayne, in the State of Ohio, have invented a Money-Drawer Treadle; and I do hereby declare that the following is a full and exact description thereof, references being had to the accompanying drawings, and the letters of reference marked thereon.

The nature of my invention consists in an arrangement of levers and rod, by which a catch is operated, which connects with the back part of a money-drawer.

To enable others skilled in the art to make and use my invention, I will proceed to describe its construction and operation.

Figure 1 represents a side view of the device.

Figure 2 represents an end view of the supporting-pieces for the levers.

The position of this treadle when in use is on the floor directly beneath the money-drawer.

D represents the floor, and F a standard, to support the rod E. This standard may be dispensed with, and the guide attached to the counter. The rod E passes through the plate s, at its lower end, and an orifice is provided in the floor for the required movement. A spiral spring, m, surrounds this rod, and rests against the lever A and plate s. This spring keeps the lever elevated as high as the overlapped condition of the levers will admit. A pin, x, connects the lever and rod. This rod is jointed or otherwise connected to a latch, which closes over the back edge of the drawer.

The pedal-lever B communicates with the lever A in the manner shown in the drawing.

At C, figs. 1 and 2, is represented a support for the levers. This support is cast in two pieces, as shown at fig. 2, this form being adapted to providing the holes for the pins n and o, which serve as fulera for the levers. This support is screwed to the floor by wood-screws passing through the part r.

Operation: The lever B, being pressed down by the foot, lowers the farther end of lever A, carrying with it the rod E, which movement disengages a catch from the money-drawer. When the foot is removed, the spring raises the levers to former position, and this throws the latch and fastens the drawer.

What I claim as my invention, and desire to secure by Letters Patent, is—

The combination and arrangement of the levers A and B, the fulcrum-support C, and spring m, or its equivalent, in the manner substantially as described, and for the purpose specified.
